[57] CLAIM

The ornamental design for a combined panty and bra hanger, as shown and described.

DESCRIPTION

FIG. 1 is a front elevational view of a combined panty and bra hanger showing our new design, the reverse side being a mirror image thereof;

FIG. 2 is a top plan view thereof;

FIG. 3 is a right end elevational view thereof;

FIG. 4 is a bottom plan view thereof;

FIG. 5 is a sectional view taken in the direction of the arrows on line 5—5 of FIG. 1; and

FIG. 6 is a sectional view taken in the direction of the arrows on line 6—6 of FIG. 1.

FIG. 3

FIG. 1

FIG. 2

FIG. 4

FIG. 5
